UNITED STATES PATENT OFFICE.

WILBUR FISK CRAFTS, OF NEW YORK, N. Y.

DESIGN FOR A FINGER-RING.

SPECIFICATION forming part of Design No. 15,711, dated January 13, 1885.

Application filed September 1, 1884. Term of patent 3½ years.

To all whom it may concern:

Be it known that I, WILBUR F. CRAFTS, a citizen of the United States, and a resident of New York, in the county of New York and

5 State of New York, have invented and produced a new and original Design for Finger-Rings, of which the following is a specification, reference being had to the accompanying drawing, forming part thereof.

10 The figure is a top plan view of the ring shown as much enlarged.

The leading features of my design consist of a band for encircling the finger, said band bearing a shield of the form known as "cru-
15 sader's," but having the lower point and up-

per corners thereof truncated, as shown. This shield bears the stars and stripes, as in the arms of the United States, a cross being displayed in the center, as shown.

I claim—

20 The design for finger-rings herein shown and described.

Signed at New York, in the county of New York and State of New York, this 21st day of June, A. D. 1884.

WILBUR FISK CRAFTS.
